UNITED STATES PATENT OFFICE

JOHN M. BRUNSWICK, OF CINCINNATI, OHIO.

DESIGN FOR A GAME-TABLE.

Specification forming part of Design No. 7,437, dated May 19, 1874; application filed May 11, 1874.
 [Term of Patent 3½ years.]

To all whom it may concern:

Be it known that I, JOHN M. BRUNSWICK, of Cincinnati, in the county of Hamilton and State of Ohio, have invented a Design for a Game-Table, of which the following is a specification:

The nature of my invention is fully represented in the accompanying illustrations, to which reference is made.

A represents a bagatelle-table, having a circular head, a square or straight foot, and two parallel sides, properly cushioned. B is a head-piece, triangular in outline, formed of two concave segments, and a convex one,

being that part of the included circular end of the table. In the concave sides of this head-piece arched openings are cut, each duly numbered, and leading to alleys under the bed which return the balls to the foot of the table.

I make no claim to the invention of the game-table, as such; but,

What I claim as my invention is—

The design for the head-piece B of the game-table A, substantially as described and shown.

JOHN M. BRUNSWICK.
